[57] CLAIM

I claim the ornamental design for a hose clip, as shown and described.

DESCRIPTION

FIG. 1 is a perspective view of the hose clip of the present invention.

FIG. 2 is a front elevational view thereof.

FIG. 3 is a rear elevational view thereof.

FIG. 4 is a top plan view thereof.

FIG. 5 is a bottom plan view thereof.

FIG. 6 is a side elevational view thereof as viewed from the right of FIG 2; and,

FIG. 7 is a side elevational view thereof taken from the left of FIG. 2.
